UNITED STATES PATENT OFFICE.

FREDERICK A. ENGLISH, OF CHICAGO, ILLINOIS, ASSIGNOR TO BIRTMAN ELECTRIC CO.,
OF CHICAGO, ILLINOIS, A CORPORATION OF ILLINOIS.

ELECTRICALLY-HEATED CURLING-IRON.

1,073,336.

Specification of Letters Patent.

Patented Sept. 16, 1913.

Application filed April 14, 1913. Serial No. 761,085.

To all whom it may concern:

Be it known that I, FREDERICK A. ENGLISH, a citizen of the United States, residing at Chicago, in the county of Cook and State 5 of Illinois, have invented a new and useful Improvement in Electrically-Heated Curling-Irons, of which the following is a specification.

My invention relates to an improvement 10 in the class of curling-irons in which the legs are hollow and contain electric resistance coils as the medium for heating them.

The object of my invention is to provide 15 a simple device on the handle of the article, through the medium of which to make electric connection of the current-supplying conducting-wires with the coil or coils, and which shall permit rotation of the article for winding the hair about it without twisting 20 the wires; and my further object is to provide means for shielding the electrical contacts at the pivotal joint of curling-irons having two jaws, whereby the contacts shall be protected against wear from rubbing 25 against each other in working the jaws to open and close them.

In the accompanying drawing, Figure 1 is a view in elevation of a pair of curling-irons provided with my improvement; Fig. 2 is an enlarged broken section on the irregular line 2, Fig. 1; Fig. 3 is a broken view showing a section of one of the two pivotal members of the curling-irons on line 3, Fig. 2, with the shielded contact-strips in elevation on that member; Fig. 4 is a broken view showing a section of the other member of the curling-irons on line 4, Fig. 2, with the contact-strips thereon in elevation; Fig. 5 is an enlarged view in elevation 40 of one half of the divided ferrule carrying contact-making connections; Fig. 6 is a view in elevation of the button which screws upon an end of one of the handles for securing the ferrule loosely in place thereon to permit the handle to rotate in it, and Fig. 7 is an enlarged broken view showing a section taken on line 7, Fig. 1.

The curling-irons shown have two hollow jaws or legs 8 and 9, the former being generally cylindrical and the latter having a concave face to receive the companion-jaw, the jaws containing, respectively, a heating-element shown as an electrical resistance coil 10, and a similar heating-element 11; but these parts need present no features of

novelty, and the ferrule-feature of my invention, hereinafter described, is advantageously useful on the handle of a curling-iron having only one hollow leg containing a resistance-coil. The jaw 8 terminates at 60 its inner end in a circular cup 12 having a central pivot-pin 13, and the jaw 9 terminates at its corresponding end in a similar, centrally-perforated, cup 14 provided with a handle 15 having an extension of insulating 65 material, while a hollow handle 16, having an extension of the same material is provided on the cup 12. The terminals of the coil 10 are secured, respectively, to contact-strips 17 and 18 (Fig. 4) secured on a block 70 19 of insulating material confined about the pin 13 in the cup 12, and wires 20 and 21 connect these strips, respectively, with metal contact-rings 22 and 23 secured about the reduced rear-end portion, of insulating 75 material, of the handle 16. A block 24 of insulating material, centrally perforated for the passage through it of the pivot-pin, carries contact-strips 25 and 26 with which, respectively, the terminals of the coil 11 are 80 connected; and spring-shields 27 and 28 of thin sheet-metal are riveted through the insulating block, as shown in Fig. 2, to extend about its opposite edges and at their free, springy sections respectively over the strips 85 25 and 26, with which they are thus electrically connected.

To assemble the two jaw-members of the device, the cups are brought together at their open faces, causing the pivot-pin 13 to 90 pass through the cup 14; and the cups are rotatably fastened together by screwing a nut 29 on the threaded projecting end of the pin. A pair of insulated conducting wires 30 and 31, contained in a cable 32, connect 95 electrically at one end with the rings 22 and 23 (Fig. 5), and are adapted in a usual way, as by means of a porcelain contact-plug (not shown) connected with their opposite end and insertible into the socket of an incandescent electric lamp (not shown), to be coupled with the supply of electric current, for heating the resistance-coils and thereby heating the jaws 8 and 9.

For electrically connecting the conductor 32 with the rings 22 and 23, I provide a ferrule 33 of wood or other suitable insulating material, formed preferably in two sections of general cylindrical shape, with corresponding flange-extensions 34, 34 having 110

2
half-nipples 35 projecting from them, and through which flanges the two ferrule-sections are fastened together by a small screw-bolt 36, to produce the cylindrical portion 5 of the ferrule and bring together face to face the flanges and the nipple-sections to form the nipple, through which the cable enters the ferrule. In the cylindrical portion of the ferrule, near its opposite ends, 10 are confined metal rings 37 and 38 having perforated radial extensions 39, with which the wires 30 and 31 are respectively connected. The ferrule fits loosely about the reduced end-portion of the handle; and when 15 in that position, wherein it is held by a button 40 screwed against it upon the handle-end, the ring 37 contacts with the ring 22, the ring 38 contacts with the ring 23, thus electrically connecting the cable with the re- 20 sistance-coils at the wires 20 and 21, which pass to the rings 22 and 23 through holes 41 in the reduced portion of the hollow handle; and the curling-irons may be turned by the user, for winding the hair about the 25 jaws, freely without twisting the cable, owing to the loose connection of the ferrule with the handle 16.

In opening and closing the jaws, the interposition of the spring shields 27, 28 between the contacts-strips 18, 25, and 17, 26, 30 prevents these strips and the wire-connections therewith from rubbing against each other and, therefore, from wear and consequent disorganization of the electrical connections. 35

I realize that considerable variation is possible in the details of construction thus specifically shown and described, and I do not intend by illustrating a single, specific or 40 preferred embodiment of my invention to be limited thereto; my intention being in the appended claims to claim protection upon all the novelty there may be in my invention as broadly as the state of the art will 45 permit.

What I claim as new and desire to secure by Letters Patent, is:—

1. In an electrically-heated curling iron, 50 the combination of a hollow leg provided with a hollow insulating handle having a reduced end-portion surrounded by a pair of

metal rings, a heating-element in the leg having its terminals connected with said rings, a ferrule of insulating material loosely surrounding said reduced handle-portion, formed of a pair of semi-cylindrical sections each having a flange-extension and a nipple-section thereon and bolted together through the flange-extensions, with metal rings confined in the cylindrical portion of the ferrule to contact, respectively, with said rings on the handle, and conducting-wires connected with said rings in the ferrule, for the purpose set forth. 55 60 65

2. In an electrically-heated curling iron, 65 the combination of a pair of hollow jaws terminating in cups having handles extending from them and at which they are pivotally connected together, heating-elements in the jaws, insulated contact-strips in one 70 cup, with which the terminals of the corresponding element are connected, insulated contact-strips in the other cup, with which the terminals of the corresponding element are connected, spring-shields connected with 75 and extending over the contact-strips in the last-named cup, and current-supplying conducting-wires leading to said strips, for the purpose set forth.

3. In an electrically-heated curling iron, 80 the combination of a pair of hollow jaws terminating in cups having handles extending from them and at which they are pivotally connected together, heating-elements in the jaws, insulated contact-strips in one cup, 85 with which the terminals of the corresponding element are connected, insulated contact-strips in the other cup, with which the terminals of the corresponding element are connected and having wires leading from 90 them along the handle on that cup, spring-shields connected with and extending over the contact-strips in the first-named cup, current-supplying wires, and means for connecting the current-supplying wires with 95 said first-named wires, for the purpose set forth.

FREDERICK A. ENGLISH.
